UNITED STATES PATENT OFFICE

HENRY VIEREGG, OF GRAND ISLAND, NEBRASKA.

AUTOMATIC FIRE ESCAPE.

Application filed November 29, 1921. Serial No. 518,617.

To all whom it may concern:

Be it known that I, HENRY VIEREGG, a citizen of the United States, and a resident of Grand Island, in the county of Hall and State of Nebraska, have invented a new and Improved Automatic Fire Escape, of which the following is a full, clear, and exact description.

This invention relates to an automatic fire escape, and has for an object the provision of means whereby in escaping from a fire a person need merely attach the device to some suitable support and then grip a rope, whereupon his weight effectively operates the device, at the same time causing a regulation of the speed of movement of the rope to prevent his speed of descent from being too great.

Another object resides in the provision of centrifugally operated braking means whereby the resistance offered to the movement of the rope is dependent upon the weight applied to the rope.

A further object resides in the particular construction and arrangement of parts which are hereinafter described and claimed and shown in the accompanying drawings.

The invention is illustrated in the drawings, of which—

Figure 1 is a front view of the device.

Fig. 2 is a side elevation.

Fig. 3 is a section taken on the line 3—3 of Fig. 1.

As shown in the drawings, the preferred form of my invention comprises a casing formed of spaced plates 1 and 2 having flanges such as 3 and 4 connected by any suitable means such as screws 5 and nuts 6.

A threaded shaft 7 is journaled in any suitable manner between the walls of this casing and within the casing supports a pulley 8. This pulley is provided with tapered inner walls, as shown particularly in Fig. 3, on which are disposed a plurality of spaced ribs 9 which act as means for clamping or frictionally gripping a rope or other load-carrying means disposed to pass over the pulley. One end of this shaft, as 10 projects beyond the casing and is provided with a slot 11 through which a plate 12 passes. The plate is fastened in position by means of a pin 13 which passes through the shaft in the plate. This plate 12 extends above and below the shaft and lies adjacent one face of the casing. At each end of the

suitable material, which are connected by a link 15 to the plate 12. The connection between the weights 14 and the plate 12 is a pivot connection, such as a pivot screw 16. The connection or link 15 joining each weight with the plate is bent, and on its inner end adjacent the wall of the casing is provided with a friction surface such as 17 which may be made of any suitable friction material such as rubber, leather or fabric. As the shaft 7 revolves, especially when the casing is disposed in a vertical position, the effect of gravity and centrifugal force on the lower weight will be to press the friction surface 17 rather firmly against the wall of the casing as the weight is moving in the lower half of its rotation; whereas, the force of gravity and the centrifugal force will tend to oppose each other when the weight is in the upper portion of its rotation. In this way, therefore, as the shaft rotates there is an intermittent production of resistance to the movement of the shaft on the part of this centrifugal controller which will regulate the speed at which the shaft can move. Of course, the heavier the weight on the rope, the faster the shaft will tend to move, and, consequently, the same resistance will be offered to its movement by the controller. The bottom of the casing beneath the pulley is open and from this portion of the casing extends downwardly a plate 18. On this plate are disposed a plurality of spaced bars or pins 19 and a plurality of pairs of curved clamping plates 20. As the rope passes over the pulley, it is alternately disposed between the clamping plates 20 and then separated by

the spacer bars or pins 19. As the strands 21 of the rope pass between the sets of clamping plates they are naturally subject to considerably more friction than would normally be the case, and this tendency aids in the regulation of the speed of the rope. Furthermore, as the rope passes around the pins 19 and between the plates 20, it is disposed in a curved manner so that as the weight subjects the rope to a certain stress, the friction produced between the rope and the pins and plates will be roughly proportional to the weight and, therefore, these devices will aid the centrifugal control to keep the speed more uniform.

The upper end of the casing may be provided in any suitable manner with an ex- 110 tended upper end 22 for the reception of a
